UNITED STATES PATENT OFFICE

1,988,410

POWDER SIFTER.

Arthur Bates, North Attleboro, Mass., assignor to
Evans Case Company, North Attleboro, Mass., a corporation of Massachusetts

Application July 12, 1934, Serial No. 734,850

12 Claims.

(Cl. 132—82)

The present invention relates to powder sifters adapted to be inserted into compacts. When loose powder is carried in a compact some provision must be made for covering the powder and keeping it in the proper portion of the receptacle and keeping it from spilling and at the same time allowing it to come forth and be extracted when needed for use. Such devices are commonly termed sifters and the present invention contemplates a semi-rigid more or less elastic device which will normally snugly fit the powder cavity and is provided with a foraminous section through which the powder may be extracted.

One form of the invention may take is shown in the accompanying drawing in which Figure 1 is a top plan view of one type of compact open and provided with a sifter of the present invention. Fig. 2 is a longitudinal vertical section on the line 2—2 of Fig. 1. Fig. 3 is a transverse vertical section on the line 3—3 of Fig. 1 the covering of the compact being shown closed and a powder pad being shown in place. Fig. 4 is a plan view of a sifter removed from the compact.

The drawing illustrates one form of compact comprising a body 10 and a cover 11 hinged thereto at 12. In the body 10 is a cavity 13 for receiving loose powder. As shown in Fig. 1 the cavity may be more or less rectangular in plan and having curved corners. The body 10 of the compact is illustrated as tapered in thickness as shown in Fig. 2 and correspondingly the powder cavity 13 is shown tapered being shallower at the lower end.

The form of the compact and the powder cavity forms no part of the present invention which may be incorporated in a compact of any suitable form. As is well known in the art of the powder cavity may be circular or of other desirable shape and the depth of the powder cavity may be uniform or may vary in any way desired. The sifter will be formed or adapted to correspond with the shape of the powder cavity.

In the drawing a sifter is shown adapted to fit into the powder cavity. The sifter illustrated comprises an outer coating of pile fabric such as velvet or the like 14 which may be of any suitable color to match or correspond with the compact or the powder used. The velvet 14 is mounted on a backing of stiffening buckram 15. The velvet will preferably be attached to the buckram throughout its entire surface with glue sizing or other suitable material. Compound sheets made up of layers of buckram and velvet may be formed in dies or the like and may be severed or cut by any suitable means either before, after or

while shaping. Preferably the dies will be heated. The formed sifter is shown as provided with integral more or less vertical sides 16 corresponding with and closely engaging the side walls 17 of the powder cavity 13. Likewise there is a longer end member 18 corresponding with and more or less closely engaging the longer end wall 19 of the powder cavity 13. At the other end the velvet and buckram is formed into a shorter wall 20 corresponding with and more or less closely engaging the shorter end wall of the powder cavity 13. The depending edges 16, 18 and 20 of the compact support a face portion 22 which is shown connected with them by a surrounding curved edge 23 which is illustrated as rising a little above the face portion 22. The face portion 22 toward its center is cut out leaving a cavity 24 which is filled with a foraminous member 25. The depending edges 16, 18 and 20 preferably support the face at about the level of the top of the powder cavity but this is not essential and the edges may be made of any suitable dimensions. The member 25 may be of metal, silk gauze or other suitable material well known in the art. The sifter is provided with a flexible loop handle 26 preferably at one end so that it may be conveniently lifted from its normal position in the powder chamber 13. The sifter may thus be lifted out, powder put in the chamber and the sifter returned to its position. The pile of the velvet engaging the walls of the powder chamber 13 may be slightly crushed and in any event forms a friction engagement therewith and tends to hold the sifter in position over the powder.

Associated with the sifter may be a powder pad 27 which may be somewhat larger than the opening 24 but small enough to fit within the curved rim 23. As shown in Fig. 3 when the compact is closed the cover of the compact tends to hold the pad 27 against the pile of the velvet of the face member 22 and thus forms a seal preventing egress of the powder.

The combined velvet and buckram is rigid enough to normally hold its shape but it is flexible so that the sifter may be forced into the powder cavity 13 in such a way as to insure a more or less tight frictional engagement at the edges. The foraminous plate 25 is also preferably somewhat flexible. The sifter thus gives when the pad is pressed against it and powder may be extracted through the member 25 whether the powder chamber 13 is full or only partially filled.

Flexibility of the sifter has been indicated

35

50

55

(possibly exaggerated) in Fig. 4 from which it will be seen that pressure by the pad or of the finger 28 on the member 25 or on the face portion 22 may flex the sifter and cause the bottom portions of the adjacent wall to project. Of course the deformation or projection of the wall is prevented by the adjacent wall of the powder chamber 13 when the sifter is in place but it is obvious that when the sifter is in place pressure upon it to extract powder will tend to cause the lower portion of its depending walls to more closely hug the adjacent walls of the powder chamber 13. Thus when pressure is applied to the member 25 by the pad 27 to procure powder the tendency is to seal the side walls more tightly and prevent powder leaking at the sides.

A sifter the main portion of which is made of velvet mounted on buckram for stiffening has been described and these are desirable materials for a sifter but the invention is not confined to any specific materials or to any specific form.

I claim as my invention:

1. A powder sifter comprising a frame of velvet backed with buckram and provided with an aperture, and gauze stretched across the aperture and attached to the frame.
2. A powder sifter adapted to fit snugly into a powder receptacle comprising a face member having an aperture, a gauze stretched across the aperture and attached to the face member, and depending edges about the face member resting on the bottom of the receptacle and holding the face near the top of the receptacle, the face member and the edges being made of velvet backed with buckram.
3. A powder sifter adapted to fit snugly into a powder receptacle comprising a face member having an aperture, a gauze stretched across the aperture and attached to the face member, and depending edges about the face member resting on the bottom of the receptacle and holding the face near the top of the receptacle, the depending edges having compressible friction material on their outer sides.
4. A powder sifter adapted to fit snugly into a powder receptacle comprising a face member having an aperture, a gauze stretched across the aperture and attached to the face member, and depending edges about the face member resting on the bottom of the receptacle and holding the face near the top of the receptacle, the depending edges being flexible and having compressible friction material on their outer sides.
5. A powder sifter adapted to fit snugly into

a powder receptacle comprising a face member having an aperture, a gauze stretched across the aperture and attached to the face member, and depending edges about the face member resting on the bottom of the receptacle and holding the face near the top of the receptacle, the depending edges having a tendency to flex outward when pressure is put on the gauze.

6. A powder sifter comprising a frame of velvet backed with buckram having down-turned sides and provided with an aperture, and gauze stretched across the aperture and attached to the frame.

7. A powder sifter adapted to fit snugly into a powder receptacle comprising a face member having an aperture, a gauze stretched across the aperture and attached to the face member, and depending edges about the face member the edges being made of velvet backed with buckram.

8. A powder sifter adapted to fit snugly into a powder receptacle comprising a face member having an aperture, a gauze stretched across the aperture and attached to the face member, and depending edges about the face member the depending edges having compressible friction material on their outer sides.

9. A powder sifter adapted to fit snugly into a powder receptacle comprising a face member having an aperture, a gauze stretched across the aperture and attached to the face member, and depending edges about the face member the depending edges being flexible and having compressible friction material on their outer sides.

10. A powder sifter adapted to fit snugly into a powder receptacle comprising a face member having an aperture, a gauze stretched across the aperture and attached to the face member, and depending edges about the face member the depending edges having a tendency to flex outward when pressure is put on the gauze.

11. A powder sifter adapted to fit snugly into a powder receptacle comprising a face member having an aperture, a gauze stretched across the aperture and attached to the face member, and depending edges about the face member the edges being flexible and having a surface of velvet.

12. A powder sifter adapted to fit snugly into a powder receptacle comprising a face member having an aperture, a gauze stretched across the aperture and attached to the face member, and depending edges the depending edges being flexible and having compressible friction material on their outer sides.

CERTIFICATE OF CORRECTION.

Patent No. 1,988,410.

January 15, 1935.

ARTHUR BATES.

It is hereby certified that error appears in the printed specification of the above numbered patent requiring correction as follows: Page 1, first column, line 37, strike out the word "of"; and that the said Letters Patent should be read with this correction therein that the same may conform to the record of the case in the Patent Office.

Signed and sealed this 5th day of March, A. D. 1935.

Leslie Frazer
